CLAIM

The ornamental design for an X-ray tube as shown and described.

DESCRIPTION

FIG. 1 is a top-front-left perspective view of an X-ray tube according to the claimed design.

FIG. 2 is a bottom-rear-left perspective view of the X-ray tube.

FIG. 3 is a top-rear-right perspective view of the X-ray tube.

FIG. 4 is a bottom-front-right perspective view of the X-ray tube.

FIG. 5 is a bottom view of the X-ray tube.

FIG. 6 is a top view of the X-ray tube.

FIG. 7 is a front view of the X-ray tube.

FIG. 8 is a rear view of the X-ray tube.

FIG. 9 is a right side view of the X-ray tube.

FIG. 10 is a left side view of the X-ray tube and,

FIG. 11 is a sectional view of the X-ray along line 11-11 in FIG. 10.

The long-dash-short-dash broken lines in FIG. 11 of the drawings define the bounds of the claimed design and form no part thereof.

The broken line hatch shading in FIG. 11 of the drawings illustrate interior portions of the X-ray tube that form no part of the claimed design.

The dash-dot broken line in FIG. 10 of the drawings showing the sectional line forms no part of the claimed design.

The surface line shading is included for clarification purposes.

1 Claim, 11 Drawing Sheets
